UNITED STATES PATENT OFFICE.

WILLIAM J. STILLING, OF ELMHURST, NEW YORK, ASSIGNOR TO HECLA IRON WORKS,
OF BROOKLYN, NEW YORK, A CORPORATION OF NEW YORK.

OPERATING DEVICE FOR SLIDING DOORS.

1,171,004.

Specification of Letters Patent. Patented Feb. 8, 1916.

Application filed December 2, 1915. Serial No. 64,645.

To all whom it may concern:

Be it known that I, WILLIAM J. STILLING, a citizen of the United States, and a resident of Elmhurst, in the county of Queens and 5 State of New York, have invented certain new and useful Improvements in Operating Devices for Sliding Doors, of which the following is a specification.

My invention relates to improvements in 10 devices for operating double sliding doors and is particularly adapted for use on elevator doors.

The main object of my invention is the 15 construction of a novel device of the above nature which shall be simple in construction, of ease and of low cost to manufacture and by means of which a movement of one of the doors in one direction shall simultaneously produce a movement of the other door in the 20 opposite direction.

Another object of the invention is the 25 production of a device of the character above described which shall also be provided with means for automatically locking the doors when they slide into meeting or closed position.

A further object of the invention is the 30 production of novel means for assisting in the opening or closing movement of a pair of sliding doors.

With the above and further objects in view which will appear from the subjoined description, the invention consists in the construction and novel combination of parts 35 hereinafter more particularly described and then specified in the claims.

A practical embodiment of the invention is represented in the accompanying drawing forming a part of this specification, in 40 which similar characters of reference indicate corresponding parts in both the views.

In the drawing: Figure 1 is a front elevation of my improved device as applied to a pair of sliding doors. Fig. 2 is an enlarged front elevation of a portion of the 45 device.

Referring more particularly to both figures of the drawing: 1, 2 represent sliding

doors hung on suitable door hangers 3, adapted to travel on the track 4, and 5 indicates a guide or groove within which the doors slide. A link 6 is pivotally connected at one end, as at 7, to the door 1 and preferably to one of the hangers from which the door is suspended. The other end of the 55 link 6 is pivotally connected, as illustrated, to a lever 8 which is fulcrumed at 9 to a fixed support 10. The opposite end of the lever 8 is pivotally connected to a sliding block 11 adapted to slide on a rod 12 held 60 by brackets 13 secured to the door 2 by suitable bolts or rivets as shown. A spring 14, encircling the rod 12, is compressed between the lower bracket 13 and the sliding block 11 and exerts an upward pressure 65 on the sliding block.

15 indicates a vertical latch-bolt slidable in and held by brackets 16 and 17 mounted on the door 2. At or near the lower end a spring 18 encircles the latch-bolt 15 and is 70 compressed between the bracket 17 and a collar 19 fixed on the bolt 15. The action of the spring 18 against the fixed collar 19 normally forces the latch-bolt upwardly and the upward movement of the latch-bolt is 75 limited by the engagement of the fixed collar 20 with the bracket 16.

21 indicates a suitable casing (shown in section) which is preferably attached or secured to the bracket 17 and which serves 80 as a protection for, and to hide from view, the spring 18 and fixed collar 19. 22 and 23 indicate fixed collars carried by the latch-bolt 15 by means of which the latch-bolt 85 can be more firmly grasped in order to operate the same when it is desired to unlock or operate the doors. When the latch-bolt is pulled down manually, its movement is limited by a stop or fixed collar 24 which is adapted to engage or abut against the end of 90 the casing 21.

A latch 25 is pivoted at 26 to the link 6 and is provided with a slot 27 which receives a pin 28 suitably fastened to or integrally united with the link 6 and which supports 95 the latch when the latch is in normal posi-

tion and limits the movement of the latch on its pivot. The end of the pin 28 is provided with a flange or retaining member 29 for preventing any movement of the latch except an angular movement on pivot 26.

The doors are operated in the following manner: The latch-bolt 15 is pulled down against the action of the spring 18 until the latch-bolt is released from its engagement 10 with the end of the latch 25, thereby unlocking the doors. The door 2, preferably by means of the latch-bolt 15, is then thrust or pulled to the right against the action of the spring 14 and the movement of the door 2 15 to the right produces a movement of the door 1 to the left. As is obvious, a movement of one door in one direction simultaneously produces a movement of the other door in the opposite direction. After the doors, 20 in either an opening or closing movement, reach a position at which the link 8 assumes a perfectly vertical position, the spring 14, due to its upward pressure on the sliding block 11, assists the movement of the doors 25 in their travel. Upon a closing movement of the doors, and just before they slide into meeting or closed position, the latch-bolt 15 engages the under side of the latch 25 forcing the latch upward on its pivot due to the 30 action of the spring 18. When the doors meet, the latch falls and rests on pin 28 and the latch-bolt engages the end of the latch thereby automatically locking the doors.

The position of door 2 and lever 8 are 35 shown in dotted lines when the doors are wide open and the paths of travel of the ends of the lever 8 when the doors are operated are likewise shown in dotted lines.

I do not desire to limit myself to the precise details of construction and arrangement 40 herein set forth as it is manifest that various modifications may be made therein without departing from the essential features of my invention as defined in the appended 45 claims.

What I claim as my invention is:—

1. In a device for operating a pair of sliding doors in opposite directions, the combination of a link pivoted at one end to one of 50 the doors and having its other end pivotally connected to the other door, a latch on said link and a bolt movable vertically and adapted to engage said latch to lock the doors together.

55 2. In a device for simultaneously operating double parting sliding doors, the combination of a link secured to one of the doors, a lever connected to said link and the other of said doors and means engaging said lever for assisting in both the opening and closing movement of the doors.

3. In a device for simultaneously operating a pair of sliding doors, the combination of a link pivoted to one of the doors, a lever

connected to said link and to the other door 65 and a spring carried by one of the doors and exerting an upward vertical pressure against said lever for assisting in both the opening and closing movement of the doors after they have reached a predetermined position 70 in their travel.

4. In a device for simultaneously operating double parting sliding doors, the combination of a link pivotally connected to one of the doors, a lever fulcrumed to a suitable 75 support and pivotally connected at one end to said link and at the other end to the other of said doors, means engaging said link when the doors are in closed position in order to lock the same and means for assisting in 80 both the opening and closing movement of the doors.

5. In a device for simultaneously operating a pair of sliding doors, the combination of a link pivotally connected to one of the 85 doors, a lever fulcrumed to a suitable support and pivotally connected to said link and the other of said doors, a vertical latch-bolt adapted to engage the link to automatically lock the doors when they slide into closed 90 position and means for assisting in both the opening and closing movement of the doors after they have reached a predetermined position in their travel.

6. In a device for simultaneously operating a pair of sliding doors, the combination of a link pivotally connected to one of the doors, a latch pivotally connected to said link, a lever connected to said link and the other of said doors, a latch-bolt adapted to 100 engage said latch to automatically lock the doors when they slide into closed position and means for assisting the opening and closing movement of the doors.

7. In a device for simultaneously operating a pair of sliding doors, the combination of a link pivotally connected to one of the doors, a latch pivotally connected to said link, a lever fulcrumed to a suitable support and pivotally connected to said link and the other of said doors and a spring-actuated latch-bolt adapted to engage the latch to automatically lock the doors when they slide into closed position.

8. In a device for simultaneously operating a pair of sliding doors, the combination of a link pivotally connected to one of the doors, a lever fulcrumed to a suitable support and pivotally connected to said link and the other of said doors, a latch-bolt adapted 115 to engage the link to automatically lock the doors when they slide into closed position and means for retaining said latch-bolt in locked position.

9. In a device for simultaneously operating a pair of sliding doors, the combination of a link pivotally connected to one of the doors, a latch pivotally connected to said

link, a slidable block carried by a rod fastened to the other of said doors, a lever fulcrumed to a suitable support and pivotally connected to said link and said slidable block, a spring-actuated latch-bolt adapted to engage said latch to automatically lock the doors when they slide into closed position and a spring exerting pressure against said slidable block for assisting the opening 10 and closing movement of the doors after

they have reached a predetermined position in their travel.

Signed at New York, in the county of New York and State of New York this 29th day of November, A. D. 1915.

WILLIAM J. STILLING.
